UNITED STATES PATENT OFFICE

168,220

LACE FABRIC

John A. Goldberg, Massapequa, N. Y.

Application July 28, 1952, Serial No. 20,782

Term of patent 7 years

(Cl. D47—6)

To all whom it may concern:

Be it known that I, John A. Goldberg, a citizen of the United States of America, residing at Massapequa, in the county of Nassau and State of New York, have invented a new, original, and ornamental Design for a Lace Fabric, of which the following is a specification, reference being had to the accompanying drawing, forming a part thereof.

The figure is a plan view of a lace fabric, showing my new design, the dot and dash lines enclosing an area representing a repeat unit thereof.

I claim:

The ornamental design for a lace fabric, substantially as shown and described.

JOHN A. GOLDBERG.
